PROCESS AND APPARATUS FOR LIQUEFYING AND RECTIFYING
AIR OR OTHER GASEOUS MIXTURES
Filed July 31, 1930

UNITED STATES PATENT OFFICE

ISAAC H. LEVIN, OF PITTSBURGH, PENNSYLVANIA

PROCESS AND APPARATUS FOR LIQUEFYING AND RECTIFYING AIR OR OTHER
GASEOUS MIXTURES

Application filed July 31, 1930, Serial No. 472,020, and in France August 3, 1929.

- This invention relates to improvements in the process of production of liquid air or similar gases and of separating air or other gaseous mixtures into their constituents by liquefaction and rectification by the air of two or several circuits. The aim of the invention is to utilize to the maximum the relatively inexpensive source of cold as ammonia or other easily liquefiable gases.
- 10 The advantages of my invention and means for obtaining these advantages will be clearly set forth in the description of an apparatus that can be employed as a matter of example to carry out the invention. The accompanying drawing shows schematically an apparatus in which the process may be practiced.
- 15 Referring to said drawing, air or other gaseous mixtures is compressed in a compressor 6 and is supplied to an interchanger 4 as through a pipe 5. The air is compressed and purified in the usual manner before reaching 20. In interchanger 4, the air is cooled by heat transfer contact with a refrigerant such as ammonia or the like.
- 25 The refrigerating system is operated, for example, by the apparatus represented in the drawing, in which a compressor 1 is used for compressing the ammonia. The ammonia is condensed in coil 2 and expanded in valve 3. The expanded ammonia enters into interchanger 4, and comes in heat transfer contact preferably by counter current with the air to be cooled and is then again compressed and the cycle is repeated.
- 30 35 The above refrigerating cycle is given only as a matter of example, and can be varied in many ways, so long as the desired refrigerating effects are produced upon the compressed air.
- 40 A valve is provided at 7 to drain any moisture that is collected in the interchanger.
- The air leaving the interchanger 4 may be expanded into expansion valve 8, or in the expansion engines 9 and/or 10, into the interchanger 11 as through pipe 12. While several expanding means are shown, expansion can take place either through valve 8 without the use of either of the engines shown, or the expansion may take place through the engine 45 without being previously expanded in the valve. Furthermore, the work done by both engines may be combined in one unit or but a single stage engine need be used. The expansion can thus take place in either of the units shown or in the combination of all of them.
- 45 55 In addition to passing into pipe 12 the expanded air may connect to container 14, which is a collector for liquefied portions of the air or gas, as through pipe 13, and so deposit any liquefied portions that may have resulted from the expansion.
- 50 Another portion of air is compressed in 16 and passed into interchanger 18 as through pipe 17, then into interchanger 11, and gives up its heat in counter current to cold air in pipe 12. The gas is then expanded in valve 20 and partially liquefied. The liquefied gas is stored in 14. The liquid can be removed by valve 15, and the non-liquefied portion is sent into interchanger 11 through pipes 13 and 12 and then to interchanger 18 and by heat transfer with the gas entering as through 55 60 65 70 75 80 85 90 95 100 17, is brought to room temperature.
- The interchangers 11 and 18 could be united into one. It is preferable to have two interchangers, which gives one the advantage of limiting the condensation of moisture and also of frost to practically interchanger 18 and the necessary defrosting can be done without disturbing interchanger 11. The means for heating the interchanger for defrosting are not shown in the drawing. Valve 21 may be used to drain moisture out of interchanger 18.
- In this process, where a current of air is compressed then refrigerated by ammonia or other vapors of easily liquefiable gases and is expanded in an engine doing external work, the result from the point of view of production of liquid air is small but the heat content is by this means very much lowered in the order of 50 kilocalories per kilogram. The refrigerated air is used as a refrigerant on another current of air capable of absorbing this cold by heat transfer contact.
- The air to be liquefied passes through the interchangers 18 and 11. Before it is expanded it is quite warm relative to the cold vapors in pipe line 12. This permits of good

heat transfer. If one utilizes both circuits of the air at 200 atmospheres, for example, in the proportion of 1 kilogram of air of the circuit cooled by the cold non-liquefied portions of the air to 1.33 kilogram of the circuit cooled by ammonia or the like, the result will be that instead of getting about 8 calories in the form of liquid air per kilogram of air compressed by using the first circuit above 10 (i. e. the liquefaction circuit alone), this process has a value of the order of 30 calories per kilogram of air compressed of the combined circuits. These quantities are not absolute but can vary largely according to the 15 dimensions of the installation and the nature of the insulation and other conditions. The energy necessary for the production of cold by ammonia is very small in comparison with the energy necessary for the total compression of the air, the result being that one not only produces an unusual quantity of liquid air per kilogram of air treated, but also the energy to produce a kilogram of liquid air is very much reduced relative to the present practice.

The process is not limited to the means of realizing same described but can be varied considerably.

The circuit for refrigerating is not limited 30 to air even when air is to be liquefied but other gases could be used as nitrogen or hydrogen. If the gas used in the circuit for refrigerating is to be recuperated and is not the same as the gas to be liquefied, an additional inter- 35 changer or an additional set of tubes in inter-changers 11 and 18 and the necessary piping changes (which are not shown in the drawing) will have to be provided to avoid contamination between the gas in the refrigerating circuit and the vapors of the gas that is liquefied. The circuits need not be at the same pressure but the pressure and volumes should be chosen in such a manner as to obtain the necessary heat transfer and to bring 40 the cold vapors to room temperature.

I claim:

1. An apparatus for liquefying a gas comprising means for compressing a portion of the gas, means for compressing, cooling and 50 expanding a refrigerant, means to bring the contact with the compressed gas whereby the cold expanded refrigerant into heat transfer gas will be cooled and the refrigerant will be heated to room temperature, means to expand the cooled gas in an expansion valve and/or expansion engine producing external work, means to employ the cooled gas as a refrigerant to cool by heat transfer contact another portion of compressed gas whereby the 55 refrigerant will be heated to room temperature and the compressed gas will be cooled, means to expand and partially liquefy the gas.

2. An apparatus for liquefying a gas comprising means for compressing a portion of

the gas, means for compressing, cooling and expanding a refrigerant, means to bring the cold expanded refrigerant into heat transfer contact with the compressed gas whereby the gas will be cooled and the refrigerant will be heated to room temperature, means to expand and partially liquefy the cooled gas in an expansion valve and/or expansion engine producing external work, means to employ the non-liquefied portion of the gas as a refr. 70 g
erant to cool by heat transfer contact another portion of compressed gas whereby the refrigerant will be heated to room temperature and the compressed gas will be cooled, means to expand and partially liquefy the gas. 75

3. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, and using the cold expanded second portion to cool the first portion. 80

4. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, using the cold expanded second portion to cool the first portion, expanding and partially liquefying said cold first portion, and using the non-liquefied part of said first portion after 90 expansion for cooling only the first of said portions before the first portion is expanded. 100

5. A process of liquefying gas, comprising compressing one portion of gas, compressing a second portion of gas, cooling said second portion by an external refrigerant, expanding said second portion with a production of a lower temperature, and using the cold expanded second portion to cool the first portion. 105

6. A process of liquefying gas, comprising compressing one portion of gas, compressing a second portion of gas, cooling said second portion by an external refrigerant, expanding said second portion with a production of a lower temperature, expanding and partially liquefying said cold first portion, and using the non-liquefied part of said first portion after expansion for cooling only the first of said portions before the first portion is expanded. 115

7. A process of liquefying gas, comprising compressing one portion of gas, compressing a second portion of gas, cooling said second portion by non-regenerative cooling means, expanding said second portion with a production of a lower temperature, and using the cold expanded second portion to cool the first portion. 125

8. A process of liquefying gas, compris-

- ing compressing one portion of gas, compressing a second portion of gas, cooling said second portion by non-regenerative cooling means, expanding said second portion with a production of a lower temperature, expanding and partially liquefying said cold first portion, and using the non-liquefied part of said first portion after expansion for cooling only the first of said portions before the first portion is expanded. 9. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, and cooling said first portion by heat exchange with said cold expanded second portion. 10. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, and cooling said first portion by countercurrent heat exchange with said cold expanded second portion. 11. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, and cooling said first portion by heat exchange with said cold expanded second portion in such manner that the second portion is brought to substantially the temperature of the entering first portion. 12. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, and cooling said first portion by heat exchange with said cold expanded second portion while said first portion is at substantially room temperature. 13. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, and cooling said first portion by heat exchange with said cold expanded second portion while said first portion is at a substantially higher temperature than the temperature of the cooled expanded second portion before heat exchange. 14. A process of liquefying gas, comprising compressing one portion of gas, compressing a second portion of gas, cooling said second portion by an external refrigerant, expanding said second portion with a production of a lower temperature, cooling said first portion by a countercurrent heat exchange with said cold expanded second portion in such manner that the temperature of the first portion is reduced and the second portion is discharged at substantially the temperature of the entering first portion. 15. A process of liquefying gas, comprising compressing one portion of gas, compressing a second portion of gas, cooling said second portion by an external refrigerant, expanding said second portion with a production of a lower temperature, cooling said first portion by a countercurrent heat exchange with said cold expanded second portion in such manner that the temperature of the first portion is reduced to substantially that of the expanded second portion and the second portion is discharged at substantially the temperature of the entering first portion. 16. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, cooling said first portion by a countercurrent heat exchange with said cold expanded second portion in such manner that the temperature of the first portion is reduced and the second portion is discharged at substantially the temperature of the entering first portion. 17. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, cooling said first portion by a countercurrent heat exchange with said cold expanded second portion in such manner that the temperature of the first portion is reduced to substantially that of the expanded second portion and the second portion is discharged at substantially the temperature of the entering first portion. 18. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, cooling said first portion by a countercurrent heat exchange with said cold expanded second portion in such manner that the temperature of the first portion is reduced to substantially that of the expanded second portion at the discharge end and the second portion is dis-

charged at the other end at substantially the temperature of the entering first portion.

19. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, cooling said first portion by heat exchange with said cold expanded second portion, expanding and partially liquefying said cold first portion, and using the non-liquefied part of said first portion after expansion for cooling only the first of said portions before the first portion is expanded.
20. A process of liquefying gas, comprising compressing one portion of gas, compressing a second portion of gas, cooling said second portion by an external refrigerant, expanding said second portion with a production of a lower temperature, cooling said first portion by a countercurrent heat exchange with said cold expanded second portion in such manner that the temperature of the first portion is reduced to substantially that of the expanded second portion and the second portion is discharged at substantially the temperature of the entering first portion, expanding and partially liquefying said cold first portion, and using the non-liquefied part of the first portion after expansion for cooling only the first of said portions before it is expanded.

charged at the other end at substantially the temperature of the entering first portion.

19. A process of liquefying gas, comprising compressing one portion of gas, compressing a second portion of gas, cooling said second portion by a refrigerant which is more easily liquefiable than the gas which is to be liquefied, expanding said second portion with a production of a lower temperature, cooling said first portion by heat exchange with said cold expanded second portion, expanding and partially liquefying said cold first portion, and using the non-liquefied part of said first portion after expansion for cooling only the first of said portions before the first portion is expanded.

20. A process of liquefying gas, comprising compressing one portion of gas, compressing a second portion of gas, cooling said second portion by an external refrigerant, expanding said second portion with a production of a lower temperature, cooling said first portion by a countercurrent heat exchange with said cold expanded second portion in such manner that the temperature of the first portion is reduced to substantially that of the expanded second portion and the second portion is discharged at substantially the temperature of the entering first portion, expanding and partially liquefying said cold first portion, and using the non-liquefied part of the first portion after expansion for cooling only the first of said portions before it is expanded.
